UNITED STATES PATENT OFFICE.

ALFRED S. BAILEY, OF HUTCHINSON, KANSAS.

BULLET-PROOF INCLOSURE.

1,187,233.

Specification of Letters Patent. Patented June 13, 1916.

Application filed August 24, 1915. Serial No. 47,164.

To all whom it may concern:

Be it known that I, ALFRED S. BAILEY, a citizen of the United States, residing at Hutchinson, in the county of Reno and State 5 of Kansas, have invented certain new and useful Improvements in Bullet-Proof Inclosures; and I do hereby declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

This invention relates to new and useful improvements in bullet proof inclosures mounted upon wheels and adapted for use for infantry when in action.

20 The invention consists of a simple and efficient apparatus of this nature having various details of construction, combinations and arrangements of parts which will be hereinafter fully described, shown in the 25 accompanying drawings and then specifically defined in the appended claim.

My invention is illustrated in the accompanying drawings, in which:

Figure 1 is a rear elevation of the apparatus. Fig. 2 is a sectional view vertically and transversely through the same. Fig. 3 is an enlarged detail in section on line 3—3 of Fig. 1. Fig. 4 is an enlarged sectional view of a port hole.

35 Reference now being had to the details of the drawings by letter, A designates a metallic van or inclosure, made preferably of bullet proof metal, and is mounted upon wheels B, each wheel being journaled upon a shaft C and each wheel having an eccentric D which is journaled in the wall of the van at D', and E is a lever which is connected to each eccentric and is adapted to swing the same so that the lower portions of 45 the wheels may be above the lower surface of the inclosure A when the inclosure rests upon the ground. For moving the inclosure from one place to another, the levers may be operated so that the wheel will project below the lower part of the inclosure.

50 The eccentrics are provided with grooves F which, when brought into registration with grooves H formed in the wall of the inclosure, may hold the latter suspended by means of a key I passing through the reg-

istering apertures and groove. The walls of the inclosure are provided with port openings K through which rifles may be projected, each rifle being adapted to rest in a swivel bearing member L so that the person 60 within the inclosure may swing a rifle to be aimed in any direction and a small peephole M is provided whereby a person may take proper aim.

In order that the operator of the rifle may 65 have a rest, folding racks O are hinged within the casing and, when not in use, may be let down out of the way. A steering wheel, designated by letter S, is pivotally mounted upon a pin steering head S' to which a handle T is fastened, said wheel S being mounted upon a projecting member S² fixed to the inclosure.

By the provision of an apparatus embodying the features of my invention, a simple 75 and efficient bullet proof van or inclosure is provided adapted to receive a number of soldiers, provision being made for projecting guns through the various apertures in the sides and ends of the apparatus, the lower 80 portion of the inclosure being adapted to rest upon the ground when not in use and, when it is desired to move the same from one place to another, the levers may be actuated so as to elevate the inclosure to allow 85 the wheels to rest upon the ground and the persons within the inclosure may push the same from place to place.

What I claim to be new is:—

A bullet proof van comprising a frame 90 having an inclosed wall, a shaft, an eccentric secured thereto and journaled in the wall of the van, a lever fixed to the shaft affording means whereby the wheel may be raised above the bottom of the surrounding 95 wall of the van, the end and side walls of the van being provided with port holes with concaved marginal walls, semi-spherical curved bearing members secured to the inner wall and having apertures which are in 100 registration with the port holes, a spherical member swiveled in said semi-spherical bearing members and apertures in the walls of the van.

In testimony whereof I hereunto affix my 105 signature in presence of two witnesses.

ALFRED S. BAILEY.

Witnesses:

A. C. POTTER,
BESSIE L. HARTMAN.
